UNITED STATES PATENT OFFICE.

WILLIAM W. BEACH, OF NEW YORK, N. Y.

DESIGN FOR A BOTTLE AND SPREADING TIP.

SPECIFICATION forming part of Design No. 18,498, dated August 7, 1888.

Application filed May 14, 1888. Serial No. 273,913. Term of patent 14 years.

To all whom it may concern:

Be it known that I, WILLIAM W. BEACH, a citizen of the United States, residing at New York, county of New York, and State of New York, have invented a certain new, original, and useful Design for Bottle and Spreading Tip, fully described and represented in the following specification and the accompanying drawings, forming a part of the same.

- 10 This invention relates to a design for the configuration and ornamentation of a combined bottle and self-feeding spreading tip for containing and applying mucilage and other similar substances.
- 15 The essential feature of the design consists in a combined bottle and spreading tip having a shape or configuration conforming to the shape of a hand and forearm, the forearm forming the body of the bottle, or bottle proper, 20 the wrist the neck of the bottle, the body of the hand the main part of the tip or cap, and the fingers the spreader.

In the accompanying illustrations, Figure 1 is a side elevation of a combined bottle and

spreading tip or cap embodying the design. Fig. 2 is a sectional elevation of the same.

Referring to said figures, it is to be understood that A represents the body of the bottle, or bottle proper, and a the neck of the same, the bottle and its neck being made in the form of the forearm and wrist.

B represents the body of the tip or cap, which is made of the form of the body of a hand. The spreader b is formed by the fingers of the hand. The hand may be represented as either gloved or not, as may be preferred.

What I claim is—

The design for a combined bottle and spreading tip or cap having the shape herein shown and described.

In testimony whereof I have hereunto set my hand in the presence of two subscribing witnesses.

WM. W. BEACH.
